[57] CLAIM

The ornamental design for a combined cane and seat unit, as shown and described.

DESCRIPTION

FIG. 1 is a rear elevational view of a combined cane and seat unit showing my design in closed condition;

FIG. 2 is a front elevational view;

FIG. 3 is a top plan view;

FIG. 4 is a bottom plan view; and

FIG. 5 is a side elevational view of the combined cane and seat unit shown in open position for use, the side not shown being a mirror image thereof.

FIG. 6 is a right side elevational view; and

FIG. 7 is a left side elevational view thereof.
